COMBINED JACK AND WHEEL AND GEAR
PULLERFred L. Frye and John K. Frye, New Boston, Ill.,
assignors of one-half to Harry Englehart,
Davenport, Iowa

Application May 25, 1933, Serial No. 672,780

7 Claims. (Cl. 29—86)

The present invention relates to an apparatus for pulling wheels and gears which may also be used as a jack when such an apparatus is needed. Among the objects of this invention are to provide an improved apparatus of the character indicated; to provide an apparatus which is designed for various uses rather than for a single purpose; and such further objects, advantages and capabilities as will hereafter appear and as are inherent in the construction disclosed herein. Our invention further resides in the combination, construction and arrangement of parts illustrated in the accompanying drawings and, while we have shown therein what is now considered the preferred embodiment of this invention, we desire the same to be understood as illustrative only and not to be interpreted in a limiting sense.

In the drawings annexed hereto and forming a part hereof,

Fig. 1 is an elevation, partly in section and partly broken away, of an apparatus which we now consider the preferred embodiment of this invention;

Fig. 2 is a plan view of the structure shown in Fig. 1;

Fig. 3 is a longitudinal section taken substantially along the plane indicated by the line 3—3, Fig. 2;

Fig. 4 is a transverse section taken substantially along the plane indicated by the line 4—4, Fig. 1;

Fig. 5 is a fragmentary longitudinal section taken substantially along the plane indicated by the line 5—5, Fig. 4;

Figs. 6 and 7 are, respectively, plan and transverse section of an element, the use of which is indicated in Fig. 1;

Figs. 8 and 9 are, respectively, plan and section of another form of the unit shown in Figs. 6 and 7, Fig. 9 being taken substantially along the plane indicated by the line 9—9, Fig. 8;

Fig. 10 is an elevation, partly in section, of a driving pin which is used also as a wrench for turning the jack screw.

The jack shown in Fig. 3 will first be described and then the attachments and their uses will be referred to in detail. This construction comprises a base 1, a head 2, an outer tubular member 3, a middle tubular member 4, and an inner tubular member 5. Preferably the latter is made integral with the base 1 to avoid any likelihood of leakage of fluid through a movable joint between the base 1 and the tubular member 5. While we have shown the tubular members 3, 4 and 5 as being cylindrical, it will be understood that these might

be made in other forms, if desired. However, we consider the cylindrical form the most desirable for numerous reasons. Between the tubular members 4 and 5 is a piston 6 which carries at its lower end a head 7 provided with sealing means 8, as is customary. At its upper end, the piston 6 has a screw-threaded opening for the reception of the externally screw-threaded extension 9 by means of which the piston may be lengthened, when this is desirable.

The screw-threaded extension 9 has a central point 10 upon its exposed end, the same being designed to enter a corresponding depression in the end of an automobile axle to provide against inadvertent slipping of one with relation to the other. This end of the extension 9 is somewhat reduced in diameter and has a ring 11 rotatably mounted thereon. It is not essential that this ring be rotatably mounted, though we consider it desirable that it be constructed in this way. Preferably the ring 11 is roughened upon its normally upper face, as well as upon its lateral edge. However, this is not essential, though desirable. At its normally lower end, the extension 9 is somewhat reduced in diameter and has a cross-pin 12 extending therethrough, the same being intended for engagement by notches 13 in the end of the driving-pin 14. This driving-pin has a socket 15 into which the reduced end of the extension 9 enters when the driving-pin is to be used. It will be evident that this driving-pin may be used both to turn the screw 8 in the end of the piston 6 and to serve as means for transmitting driving force through the screw 8.

The base 1 has openings therethrough for the reception of bolts 17 by means of which the head and base are tied together. The openings in the base 1 are counterbored for the reception of the nuts 18, the intention being that the nuts 18 shall not project beyond the lower face of the base. Gaskets are provided between the ends of the tubular member 3 and the adjacent base and head. Also, a gasket is provided between the end of tubular member 4 and the base. When the nuts 18 are tightened up, the gaskets are compressed and prevent leakage of the fluid contained within the jack, this fluid being preferably oil.

The head 2, which is somewhat elongated, as shown in Fig. 2, has openings 20 therein which are counterbored, as indicated at 21 and 22. The openings 21 are partly spherical for the reception of the similarly shaped face of the nuts 23 which have screw-threaded connection with the hooks 24, whose hooked ends 25 are intended to engage

a gear when it is desired to pull same from a shaft. The counterboring 21 and 22 makes it possible for the hooks 24 to swing inwardly and outwardly, according to the size of the gear which it is necessary for the ends 25 to engage. With the nuts 23 and the counterborings 21 shaped as shown, it is possible for the nuts to rock with relation to the head 2 without placing any undue strain upon the hooks 24. Oil seals are shown 10 as engaging the inner and outer surfaces of the piston 6 to prevent leakage of oil along same as it is moved in and out through the head 2.

A filling opening is made in the tubular member 3 and has a screw-threaded plug 27 inserted 15 therein to prevent leakage from the interior of the device after it has been filled and the opening closed. A boss 28 is formed on the upper face of the base 1 and has a screw-threaded opening 15 therein for the reception of the screw-threaded 20 end of the pump cylinder 29 in which the pump piston 30 reciprocates. As is apparent from Fig. 1, the handle 31 is pivotally connected to the piston 30 and to the post 32. This latter has a base 33 to which it is pivotally connected and the base has screw-threaded connection with the base 1.

There is an opening in the base 1 below the lower end of the pump cylinder 29 and from this opening 35 extends a passageway 36 which is 30 intercepted by a passageway 37, having at its inner end an upwardly extending opening 38 which communicates with the chamber between the tubular members 3 and 4. In the chamber 31 is a ball valve which is pressed against its seat 35 by means of a spring mounted in the chamber or passageway. This valve serves to prevent return of oil pumped out of the reservoir between the members 3 and 4 by the pump 29, 30. A passageway 40 extends from the chamber 35 inwardly to a vertically extending passageway 41 40 communicating with the chamber below the piston 6 and between the tubular members 4 and 5. This is shown most clearly in Figs. 3 and 4. In the passageway 40 is a spring-pressed ball valve 42 which prevents return flow of oil pumped into the piston chamber by the pump 29, 30. It will thus be seen that the two ball valves operate in the same way to prevent return flow of oil from the piston chamber to the storage reservoir. The 45 details of the valve 44 are shown in Fig. 5, from which it will be seen that a passageway 45 connects a pair of passageways 46 and 47, the passageway 45 being controlled by a valve member 48. From the foregoing it will be seen that when 50 the valve 44 is opened the fluid will be permitted to flow from the piston chamber through the passageways 46, 45 and 47 into the storage reservoir. This will permit the jack piston 6 to lower, as is 55 necessary when the work of the apparatus is completed.

A hollow member 50 has its lower end reduced, as indicated at 51, in Fig. 1, and externally screw-threaded to be screwed into the correspondingly threaded opening 52 in the top of head 60 2. The piston 6 slides freely within the end 51 of member 50, just as member 8 slides freely within the tubular member 5. While the threads in the opening 52 are shown as left hand threads, it will be understood that it is immaterial whether these are right or left hand threads. However, it will be preferable to have them regular right hand threads in order to avoid confusion in use. Member 50 is provided with a lateral opening 53 and a slight end flange 54, the interior face 75 of the member 50 being slightly frusto-conical

to closely fit the outer face of the interrupted ring 55. This taper will prevent spreading of the member 55 in use and the parts may even be made of a size such that the ring will be slightly compressed under strain. Some of the members 55 are made with a smooth internal wall, as shown in Fig. 1, and some have this wall screw-threaded, as indicated in Figs. 6 and 7, so that they may be screwed to the end of a wheel hub, when pulling the wheel from the axle.

The type of construction shown in Figs. 1, 8 and 9 is used where the hub is provided with a flange which can be engaged by the ring 55, while the structure shown in Figs. 6 and 7 would, as indicated above, be used where the hub is externally screw-threaded and not provided with a flange. If, upon operation of the pump to put pressure upon a wheel or gear to cause removal thereof, it is found that same does not yield to such pressure, the driving-pin 14 may be applied to the reduced end of the extension 9 and then tapped gently with a hammer. This will tend to cause loosening of the wheel or gear from the axle or shaft so that, when the pump is actuated again, separation of the parts will 25 be likely to be caused.

If difficulty should be experienced in turning the extension 9 so as to cause it to project farther from the piston 6, the driving-pin 14 can be inserted through the base of the jack and 30 the openings 13 engaged with the pin 12, whereupon pin 14 can be turned to cause turning of the extension 9 to cause it to be retracted or projected farther. If, when it is desired to use this as a jack, the hooks 24 are not so long as to interfere, they may be left in the openings 20. However, if it is found that one or both of these is in the way, one or both of the nuts 23 may be removed so that the hooks 24 may be withdrawn from the openings 20. They will then 40 not be in the way and will not interfere with the use of the device as a jack. Whether this will have to be done or not will depend entirely upon the amount of space available for the insertion of the jack. When the structure is used as a 45 wheel or gear puller, these hooks are essential, except in a few cases in which it may be desired to remove a small gear which may be put through the end opening in member 50. Instances of the 50 possibility of such use will be so few as to be negligible and it will therefore be unnecessary to consider them further.

It will of course be understood that the specific description of structure set forth above may be departed from without departing from the spirit 55 of our invention as set forth herein and embraced in the following claims.

Having now described our invention, we claim:

1. A jack comprising a base having an up-standing tubular member provided adjacent its upper end with a liquid seal ring, a piston surrounding said tubular member and having a liquid seal in its lower end, said piston being slidable longitudinally of said tubular member, a second tubular member surrounding said piston and cooperating therewith in substantially liquid-tight relation, said second mentioned tubular member being attached to the base in liquid-tight relation, a third tubular member surrounding the first and second tubular members 65 and having liquid-tight connection with said base, there being liquid chambers between said tubular members, a head spaced from said base and connected to said second and third tubular members in liquid-tight relation, said head hav- 70 75 75

- ing an opening therethrough for the passage of whereby rotative force may be transmitted from said piston, a liquid seal in connection with said the separate means to the jack element.
5. A structure of the nature indicated comprising a body provided with a base having an aperture therethrough, a hydraulically operated element within the body capable of projection therefrom, and separate means to be inserted through the aperture in the base to engage the end of the hydraulically operated element and to transmit rotative force thereto to cause extension 10 or retraction thereof. 5
6. A structure of the nature indicated comprising a body provided with a base having an aperture therethrough, means for attaching the body to work, a jack element within said body 15 and extending substantially perpendicularly away from the base, said jack element being movable by hydraulic force, and separate means to be inserted through the aperture in the base to engage the end of the jack element and to transmit blows to the jack element, said jack element and separate means having interengaging parts whereby rotative force may be transmitted from the separate means to the jack element. 20 25
7. A structure of the nature indicated comprising a body provided with a base having an aperture therethrough, a hydraulically operated element within the body capable of projection therefrom, means for attaching the body to work, 30 with said element in contact with the work, and separate means to be inserted through the aperture in the base to engage the end of the hydraulically operated element and to transmit rotative force thereto to cause extension or re- 35 traction thereof. 35
4. A structure of the nature indicated comprising a body provided with a base having an aperture therethrough, a jack element within said body and extending substantially perpendicularly away from the base, said jack element being movable by hydraulic force, and separate means to be inserted through the aperture in the base to engage the end of the jack element and to transmit blows to the jack element, said jack element and separate means having interengaging parts
